COOLING OF HEAT ENGINES

Marcel Vullierme, Paris, France

Application March 16, 1932, Serial No. 599,296
In France March 20, 1931

4 Claims. (Cl. 123—174)

The present invention relates in general to means for cooling heat engines, such as internal combustion engines, and more particularly to means for cooling aircraft engines.

5 It has been hitherto the custom to cool engines by the use of radiators, or of apparatus in which a flat stream of liquid flows along a fixed wall such as the outer surface of the airplane body. In the first case, the weight of the conventional radiator and its resistance to forward travel are considerable, and in the second case the weight is still greater, as only one wall of the cooling device serves for the evacuation of the heat, while on the other hand the arrangement is fragile as well as bulky. It is a known fact that the resistance of the conventional exposed radiator to forward travel is proportional to the square of the speed, while the transmission of the heat to the surrounding air is only proportional to the speed itself. For this reason, attempts have been made to produce an apparatus that would offer no resistance to travel, and in which the speed of the air in contact with the cooling walls would be great.

25 The present invention consists in circulating the cooling fluid, such as water, in a device adapted to rotate at high speed in the surrounding air, or other fluid. Thus for an airplane engine, the cooling fluid may be circulated in the interior of the propeller. The propeller may be formed with apertures or recesses, reducing its weight. The engine-cooling fluid, or main fluid, may be circulated in a suitable cooling device which is cooled by means of an auxiliary fluid circulating in the recesses in the propeller.

35 The circulation of the fluid may be assured by the rotation of the propeller itself, and thus the usual pump may be eliminated. In a preferred form of construction, the conduits for the supply and the discharge of the fluid have their openings at different distances from the axis of the propeller hub, thus producing the difference of pressure required for the circulation of the liquid. The hub may be made leakproof during 40 the rotation, by the use of sheet metal plates serving to close the joint between the fixed and the movable part.

45 In one form of construction of the propeller blade, suitable holes or bores may be formed in order to contain the tubes in which the cooling fluid is circulated. The bores are preferably formed in a metallic propeller, before the blades are subjected to torsion, and each bore will preferably contain a partition by which it is divided 50 into two conduits serving respectively for the

forward and for the return circulation of the liquid.

In an effective arrangement, a stationary device may be mounted near the propeller hub, through which device the water is circulated. 5 This device is preferably provided with a circuit for the main fluid of the engine, and with a second circuit for the auxiliary fluid circulating in the blades. The fluid circulating in the propeller contacts a portion of the stationary device forming the main fluid circuit. Thus the device provides a heat exchange medium for the two fluids in the two circuits.

In the event of breakage of a tube, the cooling liquid will rapidly escape. This can be prevented by means of valves which are closed by the liquid when the latter exceeds a given speed, and thus the valve will close the inlet of the damaged tube.

The description is illustrated by the accompanying drawing which is given by way of example.

20 Figure 1 is a view in section taken through the central part of a propeller in a plane passing through the axis of rotation and through the 25 axes of the blades.

Figure 2 is a view similar to Fig. 1 of a modified form of propeller and cooling system.

30 Referring more particularly to the drawing, there is shown in Figure 1 a shaft 1 carrying a propeller, of which only the hub 2 and the stubs of the blades 3 and 4 are shown. In the hub 2 are formed two annular recesses 5 and 6. The recess 5 is deeper than recess 6 so that the outer extremity 7 of the recess 5 is annularly farther removed from the shaft than the outer extremity 8 of the recess 6, communicating with these recesses are conduits 9 and 11 and 10 and 12 respectively, the conduits being bored longitudinally of the blades. The conduits 11, 12 are 40 connected together at 13 near the end of the blade, and the conduits 9, 10 may be accordingly connected together in like manner.

35 The shaft 1 is surrounded by conduits formed by walls 14, 15, 16, which are coaxial with the shaft and extend within the hub, then expanding to form four flaring walls 17, 18, 19, 20. At the outer extremity of the conduit formed by walls 17, 18 is thus formed an outlet 21 which is radially closer to the shaft 1 than the corresponding inlet 22 of the conduit formed by walls 19, 20. The passages provided by the conduit walls 14, 15, and by the conduit walls 15, 16, are 50 respectively connected with the water cooling system of the engine driving the propeller, this 55

being readily effected, as the walls 14, 15, 16, and the flared walls 17, 18, 19, 20 have a fixed position and do not rotate with the propeller.

When the propeller is in motion, the device thus formed acts as a pump for circulating the liquid in the direction of the arrows 23, 24, 25, 26, 27 because the inlet conduit formed by walls 14 and 15 and the outlet conduit formed by walls 15 and 16 are spaced at different distances from the axis of rotation of the propeller. This construction produces in effect a U-shaped column of water, the legs of which are of unequal length, so that upon rotation of the propeller, and consequent production of centrifugal force, the legs of the column tend to equalize in length and thereby produce a movement of the fluid from the inlet conduit to the outlet. When flowing through the interior of each blade, the liquid is cooled to a great degree, owing to the speed of the air in contact with the blades. Thus the heat produced by the engine and contained in the water entering at 23 is readily imparted to the surrounding air by this device which offers practically no head resistance to the forward travel.

Figure 2 represents a propeller having two metallic blades 28, 29 which may be secured to the hub 30 in any suitable manner. The hub itself is mounted on a shaft 31. Before giving the necessary torsion to the blades 28, 29, these latter are pierced with longitudinal conduits 32, 33, 34, 35, into each of which is fitted a tube 36, divided into two conduits by a middle partition 37, which conduits are in communication at the end of the blade at 48. After the blade has been thus arranged, it is given the usual torsion in order to produce the desired pitch.

The blade is provided near its inner end with a ring 38 which serves for common circulation. The ring comprises two annular grooves 39, 40; the outer groove 39 is connected by channels 41 with the conduits 42, 43; the inner groove 40 is connected by another set of channels 44 with the conduits 45, 46.

A ring-shaped member 47 is secured to the rear side of the propeller, and in it are formed two annular recesses 49, 50, analogous to the recesses 5, 6 of Figure 1. The recess 49 is connected by a channel 51 with the groove 39 of the blade 28 and with the corresponding groove 52 of the blade 29; in like manner, the recess 50 is connected with the grooves 40 and 53.

The recesses 49, 50 contain a stationary member adapted for a cooling action between the water from the engine, or the main cooling fluid, and the liquid circulating in the blades, or the auxiliary fluid.

For this purpose, the apparatus comprises three pairs of sheet metal pieces such as 54, 55 and 56, 57, forming a torus-shaped device which has the form of a J in cross section, as observed in the figure. The main fluid enters through the pipe 58 and proceeds between the sheet metal pieces of the three pairs, thus circulating in the torus and returning to the engine through the pipe 59.

On the other hand, due to the rotation of the propeller, and in the same conditions as described in connection with Figure 1, the auxiliary fluid flows in the direction of the arrows 60, 61, thus flowing between the three pairs of closely-spaced

sheet metal pieces, whereby one fluid is cooled by the other.

The apparatus is made leakproof by means of an annular packing member 62 consisting of an elastic substance which is secured to the sheet metal piece 54 to frictionally engage a sheet metal ring 63.

To provide for the case of damage causing a considerable leakage, for instance in the conduit 46, there may be provided suitable check valves 10 such as shown at 64 to automatically close the conduit. The valve may be mounted at the end of a spring strip 65, and when the rate of flow of the liquid increases, the valve will be applied against the outlet of the conduit. 15

Having now particularly described and ascertained the nature of my invention and in what manner the same is to be performed, I declare that what I claim is:

1. For use in a vehicle a heat engine cooled by 20 a main fluid, the combination of a motive propeller driven by said engine, means for circulating said main fluid to act as a cooling medium and means for circulating a supplementary fluid in the interior of said propeller for cooling said 25 main fluid.

2. For use in a vehicle a heat engine cooled by 30 a main fluid, the combination of a motive propeller driven by said engine, means for circulating said main fluid to act as a cooling medium 35 and means for circulating a supplementary fluid in the interior of said propeller for cooling said main fluid, said propeller having a hub, a heat exchanging device located in said hub, said heat exchanging device having conduits through which 35 the fluid circulating in the propeller passes, said heat exchanging device also having conduits for the cooling of the fluid circulating in said engine.

3. In a vehicle operated by an internal combustion engine necessitating heat dissipation by 40 a circulating fluid, a drive shaft to which the power developed by said engine is transmitted, a propeller of the aeroplane type attached to and rotated by said shaft and constituting means for propelling the vehicle, a liquid circulating system 45 for cooling the engine including radially disposed conduits in the propeller, and concentric annular inlet and outlet conduits surrounding the shaft and in communication with the radial conduits in the propeller, whereby the heat of the combustion engine may be dissipated by the liquid circulating within the propeller. 50

4. In a vehicle operated by an internal combustion engine necessitating heat dissipation by a fluid circulating through a water jacket in the 55 engine, a drive shaft to which the power developed by the engine is transmitted, a propeller of the aeroplane type attached to and rotated by said shaft and constituting the means for propelling the vehicle, and a liquid circulation system 60 for cooling the engine including radially disposed conduits in the propeller and concentric annular inlet and outlet conduits surrounding the shaft communicating with the radial conduits and the water jacket whereby liquid may be circulated 65 through the water jacket and the propeller to cool the engine.

MARCEL VULLIERME.
